FRITZ LUBBERGER, OF BERLIN-SCHMARGENDORF, GERMANY, ASSIGNOR TO SIEMENS & HALSKE AKTIENGESELLSCHAFT, OF WERNERWERK, BERLIN, GERMANY.

AUTOMATIC TELEPHONE SYSTEM.

Application filed July 2, 1925, Serial No. 41,034, and in Germany July 12, 1924.

The invention relates to automatic telephone systems comprising main and sub-exchanges. The latter only contain a fraction of the switches required for setting up a connection. Their function is to concentrate the traffic over a number of lightly loaded subscribers' lines and to forward this traffic over a few trunk lines, which are thus more heavily loaded. These sub-exchanges can for example be installed in every block of mansion flats in a town and serve the traffic to the subscribers thereat. The method of operating these lines should be the same as that for main exchange subscribers, because the subscribers of a town cannot be required to observe two different ways of setting up calls for a business address and for a private address. Hence the subscriber's station must therefore be provided with the standard instrument without keys or the like. All the operations called for by the tariff, such as single metering, repeated metering and time metering of suburban calls, and releasing a local connection for the benefit of toll calls, must be the same for sub-exchange subscribers as for other subscribers' lines, because all the traffic must be able to pass over the switches at the main exchange. The amount of manual attention required by the sub-exchange should be reduced to a minimum. Hence it is desirable that all switching operations should be effected by means of relays and no batteries of accumulators should be installed. Arrangements are known whereby battery feed current for subscribers' lines such as extension stations is passed over one lead for calls to the town area, and whereby battery current constantly passes over the other lead for feeding the calls set up between subscribers of the same sub-exchange. The main object of the invention is to enable the different operations to be performed, which mostly are combined with the release (for example metering and toll calls). The time zone metering can only take place at the end of the conversation, because the duration of the call affects the amount to be metered, and local calls may have to be released compulsorily and prematurely for the benefit of toll calls. Hence

the invention consists in locating at the main exchange the point from which all the connections are released, this point being under the control of the feeding bridges and of devices for metering and for toll calls or the like. Hence none of these devices for effecting these special operations need be located at the sub-exchange.

The Figure 1 shows the circuits of the sub-exchange; they form a relay system. All the parts numbered 100 designate apparatus belonging to the both-way trunk line VL I. The parts numbered 200 belong to a number impulse receiving switch, which is used for selecting a sub-exchange subscriber's line. The switch is associated with the trunk line VL I. All the parts numbered 300 belong to a subscriber's line. Several trunk lines can be provided. Fig. 1 in several places indicates a second trunk line VL II, which will be more particularly referred to hereafter. In place of the single subscriber's line 300, any number of subscribers' lines can be installed without altering the circuits. The condenser COU supports the energization of the relays of the sub-exchange, which likewise obtain their energizing current over the choking devices DR 100 and R 400.

The Fig. 2 shows the arrangement of the main exchange. VW 500 is a preselector at the end of the trunk line VL I. All the parts numbered 500 belong to this preselector. All the parts numbered 400 belong to a relay set, which is associated with the trunk line VL I.

A preselector VWH indicates a subscriber's connection to the main exchange. GW 600 is a first group selector, which for example is assumed to be a switch having lifting and rotary motion. A second preselector can be inserted between the preselector and this group selector, but for the sake of simplicity, such a second preselector has been omitted.

GW 700 is a further group selector. It can form a second or third group selector or the like. The type of this switch is of little importance.

The Fig. 2 only shows those circuits of a known system that are required for describing the present invention. (See for example the description of the Siemens &

Halske system in Lubberger's book entitled "Fernsprechanlagen mit Wählerbetrieb" second edition.)

5 The subscriber N 300 (Fig. 1) sets up a call to a suburb.

On taking down his receiver, the following circuit is closed:

10 1. Earth, calling relay A 300, back contact t 304, number dial contact nu 300, subscriber's instrument N 300, back contacts t 302 and asp 202, choke coil Dr 100, lead bd 103 of the trunk line VL I (Fig. 2), relay R 400, back contacts v 401 and cf 401, battery, earth. The relays A 300 and R 400 operate.

15 At the sub-exchange the relay A 300 closes the circuit:

20 1^a. Earth, front contact a 301, coupling relay K 100, winding I, lead cd 101, relay C 100 winding I, back contacts d 103, zv 103 and asp 201, lead $batt$ 101, choking coil Dr 100 and thence as above described. The relays K 100 and C 100 operate. The back contact c 101 disconnects the impulse relay AR 100 provided for incoming calls; the back contact c 102 disconnects the number receiver NE 200.

25 The coupling relay K 100 at its front contacts k 101 and 102 connects the speaking leads ad 102, bd 102 of the calling line N 300 to the leads ad 101 and bd 101 of the trunk line VL I. A condenser CO 101 prevents direct current passing from the lead bd 101 to the lead bd 103. The front contact k 103 closes the following circuit:

30 2. Earth, cut-off relay T 300, lead dd 102, front contact k 103, coupling relay K 100 winding II, lead dd 101, relay C 100 winding II, battery lead $batt$ 101.

35 The front contacts k 104 and k 105 prepare the meter circuit by connecting it to the trunk line VL I. The cut-off relay T 300 opens the calling circuit at the back contacts t 302 and t 304; at the front contacts t 301 and t 303 it connects the trunk line VL I to the subscriber's line; and at the front contact t 305 it short circuits the calling relay A 300. The relays T 300, K 100 and C 100 remain energized until the release of the connection.

40 At the main exchange (Fig. 2) the calling relay R 500 of the preselector VW 500 is connected to battery over the front contact r 401 of the relay R 400. When the calling station N 300 is switched through to the trunk line VL I, the calling circuit for the preselector (Fig. 2) is closed over:

45 3. Earth, battery, front contact r 401, calling relay R 500, back contact t 501, lead ad 103 (Fig. 1) back contact l 103, lead ad 101, front contact k 101, lead ad 102, front contact t 301, subscriber N 300 number dial contact 300, front contact t 303, lead bd 102, front contact k 102, lead bd 101, relay

B 100, earth. The relays B 100 and R 500 operate. The former closes at its front contact b 101 the following circuit:

50 4. Earth, front contact b 101, relay D 100 winding I, battery lead $batt$ 101. The relay D 100 operates. At the back contact d 103 it opens the circuit (over lead cd 101) for taking the trunk line VL I into use. At the front contact d 104 it switches over the battery lead $batt$ 101 to the circuit for taking the trunk line VL II into use, thus rendering the second trunk line accessible.

55 At the main exchange (Fig. 2) the preselector VW 500 is started up:

60 5. Earth, battery, front contact r 502, back contact t 504, rotary magnet D 500, interrupter, earth. The preselector rotates until an idle group selector is found, whereupon the following test circuit is closed:

65 6. Earth, battery, front contact r 501, cut-off relay T 500 windings II and I, wiper vvc of the preselector, lead cd 601, relay C 600 winding I, off normal contact k 601, earth. The relays T 500 and C 600 operate. The back contact t 501 disconnects the calling relay R 500, while the front contacts t 502 and 503 switch the trunk line VL I through to the group selector GW 600; the back contact t 504 interrupts the motor circuit of the preselector, while the front contact t 505, by short circuiting the winding II of the cut-off relay T 500, marks the line engaged in known manner. After the calling relay R 500 has been released, the marking engaged circuit is maintained over the segment Sg 500 and the wiper vwd of the preselector.

70 75 After the calling relay R 500 has been disconnected, the lead ad 103 is switched through over the preselector wiper vwa and the lead ad 601 to the line relay A 600 of the group selector, and relay A 600 is operated in the same circuit as the relay R 500 was previously operated. The following circuit is closed over the wiper vwb of the preselector:

80 8. Earth, battery, back contacts cf 401 and v 401, relay M 400, front contact t 503, preselector wiper vwb , lead bd 601, winding I of the relay B 600, earth. The relays B 600 and M 400 operate. The latter energizes the slow releasing relay V 400 over:

85 85 9. Earth, front contact m 403, relay V 400, battery, earth. The calling subscriber now hears the exchange calling signal over:

90 9. Earth, relay B 600, winding II, off-normal contact k 602, condenser CS 600, buzzer tone.

95 100 Thereupon the subscriber N 300 transmits the number impulses and his number dial at nu 300 opens and closes the loop in known manner. These interruptions cause the line relay A 600 of the group selector GW 600 to release its armature. The relay B 100 is to retain its armature attracted during the

train of impulses, this being achieved by mechanically rendering its armature slow acting. Hence the current impulses do not affect the sub-exchange. The group selector 5 is positioned by the current impulses in known manner as described in prior publications. Thereby the off-normal contacts k 601 and k 602 are opened. But the relay C 600 remains energized over the following 10 holding circuit:

10. Earth, front contact c 604, relay C 600 winding II and relay V 600 winding I, battery, earth. This also energizes the relay V 600.

15 *Multiple metering.*

When the calling subscriber hangs up his receiver, the relays B 100 and A 600 are de-energized. The former closes the following 20 circuit:

11. Earth, back contact b 102, front contact d 102, relay U 100, battery lead $batt$ 101. The back contact u 102 disconnects the condenser COU in order that this large 25 condenser shall not delay the deenergization of the holding relays by its long maintained discharge during the subsequent release. The front contact u 101 closes the metering circuit in the manner now to be described.

30 When the line relay A 600 at the group selector is deenergized, its contact a 602 short circuits the relay C 600, which releases its armature after a little while. The known descriptions of the system mention that the 35 lead bd 701 outgoing from the group selector is connected to battery for the purpose of preparing the metering operation. (One method of effecting this operation will be described hereafter for a call to the subscriber N 300.) At the group selector the 40 relay Z 600 is energized over:

12. Earth, battery on the lead bd 701, switch wiper gw 602, front contact p 602, back contacts u 601 and c 601, relay Z 600, 45 off normal contact k 603, earth. The relay Z 600 closes the following meter circuit:

13. Multiple metering device MZ, winding II of the relay V 600, front contact z 601, lead cd 601, preselector wiper vwc , cut-off 50 relay T 500 winding I, and parallel thereto meter relay ZR 500, back contact of 402, front contact t 505, segment Sg 500, pre-selector wiper vwd , battery, earth. Multiple metering devices are known. They 55 comprise for example interrupting discs, which transmit one or more earthed current impulses according to the positioning of the group selectors. It will be assumed that for the connection set up it is necessary to operate the meter three times. Hence the multiple metering device transmits three current impulses from earth. Each current impulse nearly short circuits the resistance W 601, thereby considerably increasing the current in the lead cd 601 three times in success-

sion, so that the relay ZR 500 is energized three times. These metering impulses maintain the relay V 600 energized over its winding II while they are being transmitted. At each of the three energizations of the relay 70 ZR 500, the latter closes the meter circuit for the subscriber over:

14. Earth, front contacts zr 502 and t 502, lead ad 103 (Fig. 1) back contact l 103, lead ad 101, front contact u 101, back contact $75 zv$ 101, front contact k 104, lead zd 102, meter Z 300, lead zd 103, front contact k 105, battery lead $batt$ 101.

At the end of the metering impulses, the connection is released. The relay V 600 releases and closes the release circuit for the group selector over:

15. Earth, battery, release magnet M 600, back contact v 601, off-normal contact k 603, earth. At its back contact m 601, the release 85 magnet M 600 opens the locking circuit over the lead cd 601, thus causing the release of the cut-off relay T 500 at the preselector VW 500. The front contact t 503 opens the holding circuit for the relay M 400, which in turn opens the energizing circuit for the relay V 400. The latter being very slow acting, battery is disconnected for a while from the lead bd 103 over the front contact m 401 and the back contact v 401. Hence at the 90 sub-exchange the lead $batt$ 101 is dead, and since the condenser COU is also disconnected at the back contact u 102, all the relays hitherto maintained energized are released, namely the relays C 100, K 100, T 300, D 100 100 and finally the slow acting relay U 100. Thus all the relays at the sub-exchange have been returned to their normal position. At the main exchange the relay R 400 is de-energized. During the short interval between the release of the relay T 500 and the release of the relay R 400, the calling relay R 500 is connected to the lead ad 103 over the front contact r 401 and the back contact t 501; but the contact u 103 at the sub-ex- 110 change prevents the relay operating during this interval. The relay U 100 being slightly slow in releasing, the circuit over:

16. Lead ad 101, back contacts u 103, c 101 and br 101, calling relay AR 100, earth, is 115 not closed until the contact r 401 at the repeater has opened in a reliable manner. The release of the relay T 500 enables the pre-selector VW 500 to return to its normal position.

17. Earth, interrupter, motor magnet D 500, back contact t 504, segment Sg 500, pre-selector wiper vwd , battery, earth. This circuit remains closed until the wiper vwd leaves the segment Sg 500.

125 *Release without metering.*

Should the wanted subscriber fail to answer the call or be engaged, there will be no 130 metering potential (battery) on the lead bd

701 outgoing from the group selector. Hence the metering relay Z 600 does not operate and no metering impulses are transmitted. A little while after the contact *c* 604 has been opened, the slow acting relay V 600 will release its armature and will bring about the release without the meter having been operated.

Call to the subscriber N 300.

10 A subscriber NH (Fig. 2) of the main exchange is to call the subscriber N 300. The latter is reached over the number —3— of the switch at the sub-exchange. When the 15 subscriber NH takes down his receiver, the preselector VWI connects his line to the group selector GW 600; thereupon the relays TH and C 600 are operated over:

18. Earth, off-normal contact *k* 601, winding I of relay C 600, lead *cd* 601, preselector wiper *vwhc*, relay TH windings I and II, battery, earth. The subscriber positions the group selector GW 600 onto the seventh level and the connection is extended in known manner to the group selector GW 700. When it has thus been switched through, the test relay P 600 at the group selector GW 600 is operated over:

19. Earth, windings II and I of relay P 600, front contact *v* 602, wiper *gw* 603, lead *cd* 701, relay C 700, battery, earth. Thereby the relay C 700 is also operated.

20. The subscriber NH then positions the group selector GW 700 onto the fourth level and the connection is switched through to the trunk line *ad* 401, *bd* 401, *cd* 401; hence the test relay P 700 is operated over:

20. Earth, relay P 700, front contact *c* 701, wiper *gw* 703, lead *cd* 401, back contact *v* 402, preselector wiper *vvc* (in its normal position), windings I and II of relay T 500, preselector wiper *vwd*, battery, earth. The relay T 500 having likewise been operated, the relay M 400 is operated over:

21. Earth, battery, back contacts *cf* 401 and *v* 401, relay M 400, front contact *t* 503, preselector wiper *vwb*, choking coil *Dr* 402, earth. The relay M 400 energizes the relay V 400 over:

22. Earth, front contact *m* 403, relay V 400, battery, earth.

In the lead *cd* 401, the contact *m* 402 is closed before contact *v* 402 is opened. The contact *t* 502 closes the following circuit:

23. Earth, battery, relay C 400, back contact *u* 401, preselector wiper *vwa*, back contact *zr* 501, front contact *t* 502, lead *ad* 103 (Fig. 1), back contact *l* 103, lead *ad* 101, back contacts *u* 103, *c* 101 and *br* 101, calling relay AR 100, earth. The relays C 400 and AR 100 are operated.

At the repeater a relay Q 400 is operated as follows:

24. Earth, battery, relay Q 400, front con-

tacts *c* 401 and *m* 404, earth. Relay Q 400 locks itself over contact *q* 401. Relay AR 100 connects up the switch NE 200, and the energization of the relay WB 200 is caused in the following circuit:

25. Earth, relay WB 200, front contact *ar* 103, back contact *c* 102, battery lead *batt* 101, choking coil *Dr* 100, lead *bd* 103, (Fig. 2) relay R 400, front contact *m* 401, back contact *cf* 401, battery, earth. The relay R 400 also operates without having any further effect. The relay WB 200 closes the contact *ub* 201.

The calling subscriber NH transmits three current impulses whereby the relay A 600 at the group selector GW 600 is oscillated 80 three times and it closes three times the following circuit:

26. Earth, back contact *a* 601, front contacts *c* 603, *p* 601, group selector wiper *gw* 601, lead *ad* 701, front contact *p* 701, group selector wiper *gw* 701, lead *ad* 401, relay A 400, battery, earth. The relay A 400 opens three times the above described circuit over the lead *ad* 103. The relay C 400 is not to release during the short current interruptions, this being achieved by a mechanical retarding device.

The relay AR 100 (Fig. 1) oscillates three times.—First current impulse. 95

27. Battery lead *batt* 101, back contacts *c* 102 and *ar* 102, front contact *ub* 201, relay JC 200 (this does not release its armature during the impulses, because it is slow acting), back contact *diff* 202, winding I of relay J 1, back contact *p* 201, earth, and parallel thereto over T 200 winding I, earth. The relays J 1 and T 200 are operated. Relay T 200 closes the following holding circuit for itself: 100

28. Earth, winding II of relay T 200, front contact *t* 204, back contact *t* 802, front contact *ub* 202, battery, earth. Relay J 1 winding I also closes a holding circuit 105 itself: 110

29. Earth, front contact *i* 11, winding II of relay J 1, front contact *t* 203, relay P 200, back contact *c* 102, battery lead *batt* 101. The relay P 200 operates and opens its contact *p* 201. The front contact *t* 201 connects both windings of the differential relay *Diff* to earth, and it does not operate so long as the contact *ar* 102 is closed. 115

End of the first impulse. 120

The back contact *ar* 102 is opened, hence relay *Diff* operates over:

30. Earth, double front contact *t* 201, winding II of the relay *Diff*, back contact *c* 102, battery lead *batt* 101. The back contact *diff* 201 disconnects winding I of the relay *Diff* from the impulse lead, while the front

contact *diff* 203 prepares the energizing circuit for the second switch relay J 2.

Second impulse.

5 31. Battery lead *batt* 101, back contacts *c* 102 and *ar* 102, front contact *wb* 201, relay JC 200, front contact *diff* 203, winding I of relay J 2, double front contact *i* 11, earth, and parallel thereto relay T 800, earth. The 10 relay J 2 winding I and relay T 800 operate. The differential relay *Diff* remains energized over the front contact *t* 801. The contact *t* 802 opens the holding circuit of winding II of relay T 200, which is deenergized 15 and falls back. The relay P 200 remains energized in the holding circuit of relay J 2 as follows:

32. Earth, double front contact *i* 21, winding II of relay J 2, back contact *t* 202, relay 20 P 200, back contact *c* 102, battery lead *batt* 101. The relay J 1 is deenergized because its holding circuit over the winding II is opened at the contact *t* 203.

25 *End of the second impulse.*

The relay AR 100 is again operated. The relay T 800 releases, because the battery circuit is interrupted at the back contact *ar* 102. The front contact *t* 801 opens the holding circuit of relay *Diff*, which thereupon releases.

Third impulse.

35 The relay AR 100 again releases and closes the following circuit:

33. Battery lead *batt* 101, back contacts *c* 102 and *ar* 102, front contact *wb* 201, relay JC 200, back contact *diff* 202, third switch relay J 3 winding I, double front contact *i* 21, earth, and parallel thereto relay T 200 winding I, earth. The relays J 3 and T 200 operate. The front contact *t* 201 prepares the circuit for energizing the relay *Diff*, and at contact *t* 203 it closes the following holding circuit for relay J 3:

34. Earth, double front contact *i* 31, winding II of relay J 3, front contact *t* 203, back contact *c* 102, battery lead *batt* 101. The front contact *t* 204 closes the holding circuit 50 for relay T 200 over its winding II.

End of the third impulse.

The relay AR remains permanently energized, because the numerical selection has 55 been completed. Hence relay JC 200 after a little while releases its armature. Its back contact *ic* 201 closes the following circuit:

35. Earth, relay *Asp* 200, back contact *ic* 201, front contact *p* 202, relay M 200, battery lead *batt* 101. The relays M 200 and *Asp* 200 operate. The latter at its contact *asp* 201 opens the taking into use circuit, so that during the succeeding testing time no subscriber of the sub-exchange can take a

trunk line into use. The second back contact *asp* 202 opens the energizing circuit of the calling relay A 300, etc., so that only the calling relay of the wanted subscriber N 300 can be operated. The front contact *m* 202 closes the following exciting or test circuit:

36. Battery lead *batt* 101, front contact *m* 202, relay F 200 (which is not sensitive), front contact *i* 32, relay A 300, earth. Relay A 300 operates, while relay F 200 does not 75 attract its armature. The relay A 300 closes all its contacts *a* 301, etc. (*a* 302 in a corresponding position in the trunk line VL II, is not shown). The relay M 200 has enabled the trunk line to be taken into use over the 80 contact *m* 201 after it was marked engaged by contact *asp* 201. Front contact *a* 301 closes the following coupling circuit:

37. Earth, front contact *a* 301, winding I of relay K 100, lead *cd* 101, winding I of 85 relay C 100, front contact *m* 201, ringing relay L 100, battery lead *batt* 101. The relays K 100 and L 100 operate. The former (K 100) couples the wanted line N 300 to the trunk line VL I in the manner above described, and also closes the holding circuit 90 over:

38. Earth, relay T 300, lead *dd* 102, front contact *k* 103, relay K 100 winding II, lead *dd* 101, winding II of relay C 100, battery 95 lead *batt* 101. The relay T 300 switches the line through at the contacts *t* 301 and *t* 303, and at *t* 305 it short circuits the relay A. This short circuit so increases the current in the relay F 200 that it operates without having any action at the present time.

The ringing relay L 100 at the back contact *l* 101 disconnects the busy tone relay BR 100 before the energizing circuit is closed at contact *f* 201. Contact *l* 102 closes 105 a holding circuit for the relay L 100 as follows:

39. Battery lead *batt* 101, ringing relay L 100, front contact *l* 102, back contact *b* 102, earth. The front contact *l* 104 switches over the lead *ad* 101 to the source of ringing current:

40. Source of ringing current, front contact *l* 104, lead *ad* 101, front contact *k* 101, lead *ad* 102, front contact *t* 301, subscriber's instrument N 300, number dial contact *nu* 300, front contact *t* 303, lead *bd* 102, front contact *k* 102, lead *bd* 101, relay B 100, earth. The relay B 100 is not operated by 110 alternating current.

The relay C 100 at contact *c* 102 opens the holding circuit for all the relays of the switch NE 200, hence the relay P 200 opens the contact *p* 202, thereby causing the relays M 200 and *Asp* 200 to release. This restores 115 (at *asp* 201) the possibility for the other trunk lines VL II etc. to be taken into use. The contact *c* 101 disconnects the calling

relay AR 100 and opens the lead *ad* 101. At the main exchange, the relay C 400 releases its armature and the relay F 400 is operated over:

5 41. Earth, battery, relay F 400, back contact *c* 402, front contacts *q* 402 and *m* 404, earth. The relay locks itself over contact *f* 401. When the subscriber N 300 answers the call, the transmitter feed current circuit is 10 closed as follows:

13 42. Earth, relay B 100, lead *bd* 101, front contact *k* 102, lead *bd* 102, front contact *t* 303, number dial contact *nu* 300, subscriber's instrument N 300, front contact *t* 301, lead *ad* 102, front contact *k* 101, lead *ad* 101, front contact *l* 104, battery in the ringing circuit.

23 43. The relay B, upon energizing, at contact *b* 102 interrupts the holding circuit for the ringing relay L 100, which then switches the lead *ad* 101 back to the lead *ad* 103. At the main exchange the relay C 400 is now operated for the second time, and the metering relay Z 400 is energized as follows:

20 43. Earth, battery, relay Z 400, back contact *cf* 403, front contacts *f* 402, *c* 403, *q* 402 and *m* 404, earth. The relay Z 400 locks itself over the contact *z* 402, and at contact *z* 401 it applies the metering potential battery to the leads *bd* 401 and *bd* 701. The subscribers speak to one another.

Subscriber N 300 is engaged.

35 When the subscriber's line N 300 is taken into use for incoming or outgoing calls, the relay T 300 is energized, and in every case the relay A 300 is short circuited over contact *t* 305. When the exciting circuit is closed over contact *m* 202, relay F 200 and 40 the front contact *i* 32, enough current passes to immediately energize the relay F 200. The ringing relay L 100 is not energized because relay A 300 is not energized, and therefore does not close the energizing circuit for relay L 100. Hence the busy tone relay BR 100 is energized as follows:

45 44. Battery lead *batt* 101, winding I of relay BR 100, front contact *f* 201, back contact *l* 101, earth. The relay BR 100 disconnects the calling relay AR 100 at the contact *br* 101 and locks itself in the following holding circuit:

55 45. Earth, winding II of relay D 100, winding II of relay BR 100, front contact *br* 102, back contacts *c* 101 and *u* 103, lead *ad* 101, contact *l* 103, lead *ad* 103, (Fig. 2) front contact *t* 502, back contact *zr* 501, pre-selector wiper *vwa*, back contact *a* 401, relay C 400, battery, earth. The winding III of 60 the relay BR 100 carries the busy tone *bs*, which is repeated to the winding II. This busy tone reaches the calling subscriber NH over the lead *ad* 103. The relay D 100 operates and prepares the release; the relay C

400 remains energized; while relay F 400 and later on Z 400 are not energized, hence metering does not take place.

Metering and release at the end of conversation.

70

The relay Z 400 at its contact *z* 401 has connected the metering potential battery to the leads *bd* 401 and *bd* 701. When the calling subscriber NH hangs up his receiver, the relay A 600 falls back and brings about the metering operation in the manner before described. The metering operation having been completed, the relay V 600 releases and, by opening contact *v* 602, it opens the holding circuit for the relay C 700. This also releases and at contact *c* 701, it opens the holding circuit of the relay T 500, which resumes its normal position. At contact *t* 503 the holding circuit for the relay M 400 is opened, which at contact *m* 401 disconnects battery from the lead *bd* 103. All the relays at the sub-exchange, which have been maintained energized over the battery lead *batt* 101, are released.

75

80

85

90

Release after a line has been found engaged.

At the sub-exchange, holding circuits have been established over the lead *batt* 101. The windings II of the relays BR 100 and D 100 have been connected to the lead *ad* 103. In the main exchange the holding battery is disconnected from the lead *bd* 103 at the contacts *m* 401 and *v* 401, and from the lead *ad* 103 at the contacts *t* 502 and *r* 401; thereby causing the release of the relays still locked at the sub-exchange.

95

100

105

Suppressing the metering and effecting the release when the wanted subscriber N 300 does not answer.

The second energization of the relay C 400 does not occur, at the repeater, because this energization by the feeding current would take place when the wanted subscriber answers the call. Hence the contact *c* 403 remains open and the relay Z 400 is not energized. The release is effected as before described by the deenergization of the relay M 400.

110

115

Suppressing the metering of incoming calls.

Incoming calls to the subscriber N 300 must not operate the meter Z 300. Hence, when the relay AR 100 operates, it energizes as follows a relay ZV 100, which prevents metering taking place:

120

125

46. Earth, front contact *ar* 101, relay ZV 100, battery lead *batt* 101. The relay ZV 100 locks itself over its front contact *zv* 102. The back contact *zv* 101 opens the circuit for energizing the meter Z 300. The relay ZV 100 is also used for switching over to the

trunk line VL II the taking into use circuit, which is disconnected from the line VL I at contact *zv* 103 and is connected to the line VL II at the contact *zv* 104.

5 *All trunk lines VL are engaged.*

When the taking into use circuit is switched over from the last trunk line (for example VL II), this being effected for example by the relay D 200, which corresponds to the relay D 100, the relay GB is then energized as follows:

47. Battery lead *batt* 101, back contact *asp* 201, contact *zv* 103 (or *zv* 104), front contacts *d* 104 and *d* II, relay GB, earth. This relay connects a busy tone to the calling relays A 300 etc. over:

48. Earth, busy tone winding *bs* I, front contacts *bg* and *a* 310, relay A 300, earth. 20 Thus the calling subscriber is notified that all the trunk lines are engaged.

Local calls, that is to say calls between subscribers belonging to the same sub-exchange, are few in number when compared with the total traffic of the sub-exchange. To set up such local calls, the calling subscriber calls the wanted subscriber over the trunk line, for example VL I, and over the switches at the main exchange and a second 30 trunk line VL II.

Toll calls occur seldom for the subscribers lines, to which the present invention relates; hence a somewhat clumsy method of operating is admissible. The Fig. 2 shows one 35 method of dealing with such calls.

The toll exchange calls the wanted subscriber in the usual manner. When the subscriber answers, the toll connection is set up over this route. If the operator finds the 40 line engaged, the toll operator sets a toll offering switch on the engaged subscriber's line, this being done by setting the offering switch, by means of number impulses, in succession on the trunk lines VL I, VL II, etc., and asking for the wanted subscriber 45 N 300. The toll operator then informs the subscribers that a toll call is waiting for N 300 and that the local connection will be released. The subscriber N 300 thereupon 50 hangs up his receiver and releases the connection. Thereby one of the trunk lines has become disengaged; and the toll exchange now sets up again an ordinary connection. If at this moment the wanted subscriber 55 should also be called by another party, the toll offering procedure would have to be repeated.

The toll exchange can also compulsorily release the local connection by energizing the 60 relay CF 400 (Fig. 2) from the toll cord circuit. The relay CF 400 opens the contact *cf* 401 and thus interrupts the battery connecting lead for all the relays at the sub-exchange, thereby causing them to release.

The contact *cf* 402 opens the incoming test 65 lead, so that the trunk line cannot be called while the toll exchange is effecting the release.

The Fig. 3 shows a modification of the repeater at the main exchange. In the arrangement above described, the subscriber N 300 does not become free when he hangs up his receiver after receiving an incoming call, because the release is effected from the calling end (NH). The circuit shown in 70 Fig. 3 enables the subscriber N 300 as well as the trunk line VL to become free as soon as the receiver is hung up after every type of call. For this purpose the repeater (numbers 400 etc.) is located at the last 75 group selector, and after a call has been made to the group of stations, to which N 300 belongs, the wiper leads at the group selector are opened as soon as the receiver is hung up. 80

In the Fig. 3 the circuit of the preselector VW 500 is only indicated, it is quite similar to the circuit shown in Fig. 2.

It has already been mentioned above that for calls outgoing from the group of stations N 300, the station N 300 as well as the trunk line VL are released (become free) 90 after the receiver has been hung up at N 300 and after metering has been effected.

The method of setting up a call to the station N 300 will now be described.

The subscriber NH (Fig. 2) sets the group selector GW 600 onto the ninth level. When it is switched through to the group selector GW 900 (Fig. 3), the test circuit 100 (Fig. 2) is closed as follows:

49. Earth, windings II and I of relay P 600, front contact V 602, group selector wiper *gw* 603 (Fig. 3), lead *cd* 901, off-normal contact *k* 901, relays B 900 winding I and C 900 winding I, battery, earth. The relays P 600, B 900 and C 900 are operated. The front contact *c* 901 closes a holding circuit over the relay C 900 winding II independent of the off-normal contact *k* 901. At the contacts *b* 901 and *b* 902, the relay B 900 connects the line relays A 900 and B 900 winding II to the incoming speaking leads *ad* 901 and *bd* 901. The calling subscriber transmits four impulses, which cause the relay A 600 (Fig. 2) to oscillate four times. At each release, a slow acting relay U 600 is energized as follows:

50. Earth, front contact *c* 604, relay U 600, back contact *a* 602, winding I of relay V 600, battery, earth. During the transmission of impulses, the following circuit is closed by the relay U 600:

51. Earth, battery, resistance (Fig. 2), front contacts *u* 602 and *p* 602, switch wiper *gw* 602, (Fig. 3), lead *bd* 901, front contact *b* 902, winding II of relay B 900, earth. The relay B 900 remains energized during

the impulse transmission, although the off-normal contact k 901 was opened at the first step.

Each time the oscillating relay A 600 releases its armature a circuit is closed over (Fig. 2):

52. Earth, back contact a 601, front contacts c 603 and p 601, selector brush gw 601 (Fig. 3), lead ad 901, front contact b 901, 10 relay A 900, battery, earth. The latter closes the following circuit four times:

53. Earth, front contacts b 904 and a 901, lifting magnet H 900, battery, earth. The off-normal contacts k 901 and k 902 are 15 switched over at the first step.

At the end of the impulse transmission, the relay U 600 falls back at the group selector GW 600, hence the relay B 900 (Fig. 3) also releases. The contacts b 901 and b 902 20 disconnect the line relays A 900 and B 900.

Thereupon the contact b 903 closes the motor magnet circuit over:

54. Earth, back contact b 903, off-normal contact k 902, back contact p 901, front contact c 903, back contacts s 404, and a 902, rotary magnet D 900, battery, earth. Upon attracting its armature, the rotary magnet closes its contact d 901, hence the relay A 900 is operated in the following circuit:

55. Earth, front contact d 901, relay A 900, battery, earth. The latter, at its back contact a 902, opens the motor magnet circuit, hence the rotary magnet D 900 releases. Thus the relay A 900 and the rotary magnet D 900 function as a self interrupter until the switch test wiper gw 903 finds an idle line and closes the following test circuit:

56. Earth, windings I and II of relay P 900, front contact c 901, back contact s 403, switch wiper gw 903, lead cd 401, preselector wiper vwc , cut-off relay T 500 windings I and II, battery, earth. The relay P 900 opens the motor magnet circuit at the contact p 901 and at the contact p 902 it marks the selected line engaged. The contacts p 903, p 904, p 905, p 906 connect up the repeating device relay A 400, relay C 400, choking coils Dr 403 and Dr 402. The rest 50 of the setting up of the connection to the subscriber N 300 takes place in the manner previously described. It should be noted that the relay C 400 is energized until the end of the last numerical selection. Relay 55 Q 400 (Fig. 3) had also operated:

57. Earth, battery, relay Q 400, front contacts c 401 and c 904, earth. After switching through to the station N 300 has taken place at the sub-exchange, the relay C 400 60 falls back for the first time and energizes relay F 400. When the subscriber N 300 answers, the relay C 400 again operates and energizes the meter Z 400 as before described.

If the subscriber N 300 hangs up the receiver before the caller NH does so, the relay C 400 falls back a second time and energizes a relay S 400 in the following circuit:

58. Earth, battery, relay S 400, back contact c 404, double front contact z 402, front contact c 904, earth. Relay S 400 now opens the contact s 404 in the motor magnet circuit, and at the contacts s 401, s 402, s 403 it interrupts the leads to the preselector VW 75 500, whereat the cut-off relay T 500 falls back. The release of the relay T 500 renders the trunk line VL free as before described. The group selector GW 900 is not yet released. The metering circuit is prepared by the closing of the contact z 401. The metering and releasing operations for the group selectors GW 600 and GW 900 80 have been described above.

When the toll operator compulsorily releases a local connection, metering is to be suppressed. If the station N 300 has originated the call, metering can be suppressed by opening the circuit of the meter relay ZR 500 at a contact of 402 of the cut-off relay CF 400. For the purpose of suppressing the metering, of incoming calls, the metering relay Z 400 can be released by a contact of 403.

What is claimed is:

1. In a telephone system, a main and a sub-exchange, a trunk line between said exchanges, said sub-exchange containing switching equipment comprising only relays, said switching equipment automatically operating to seize said trunk in response to the initiation of a call from said sub-exchange, and directly operable by impulses received over said trunk on calls from said main exchange to select a called line in said sub-exchange.

2. In a telephone system, a main and a sub-exchange, lines in each exchange, automatic switches in the sub-exchange comprising only relays, trunk lines between said exchanges terminating in an automatic switch in the main exchange and in the switching equipment at the sub-exchange, said switching equipment operated to automatically select a trunk to the main exchange when a subscriber in the sub-exchange initiates a call and operated directly over one of said trunks to select a line in the sub-exchange when a main exchange subscriber calls a sub-exchange subscriber.

3. In a telephone system, a main and a sub-exchange, a trunk line between said exchanges, subscribers' lines terminating in said exchanges, automatic switching equipment in said exchanges, a source of current at said main exchange, means for extending a talking connection from a main exchange subscriber to a sub-exchange subscriber through

- 9 said switching equipment and over said trunk, and means for operating and holding said sub-exchange equipment by current received from said main exchange source over 5 said trunk.
- 10 4. In a telephone system, a main and a sub-exchange, a trunk line between said exchanges, said sub-exchange containing switching equipment comprising only re- 10 lays, a source of current at said main exchange, and means for feeding operating current to said sub-exchange equipment from said main exchange source over said 15 trunk line.
- 15 5. In a telephone system, a main and a sub-exchange, subscribers' lines terminating in each, automatic switches in the main exchange, relay switching equipment in said sub-exchange, trunk lines between the exchanges terminating in an automatic switch in the main and in said switching equipment in the sub-exchange, means responsive to the initiation of a call by a sub-exchange subscriber for connecting that line to an idle 20 one of said trunk lines and for operating said main exchange trunk switch to extend the connection to an idle selecting switch, and means for holding said engaged sub-exchange equipment in operated position by 25 current fed over said selected trunk line from said main exchange.
- 30 6. In a telephone system, a main and a sub-exchange, subscribers' lines terminating in said exchanges, trunk lines between said exchanges, switching devices in said exchanges, means for extending a talking connection from a calling line in said main exchange through switching devices therein over a trunk line to said sub-exchange 35 through switching devices therein to a called line, and circuit means such that during conversation current flows in the same direction over both sides of said trunk line, current being supplied to the sub-exchange subscriber's transmitter over one lead thereof, and current for holding the sub-exchange switching devices in operated position being supplied over the other side.
- 40 7. In a telephone system, a main and a sub-exchange, a two-way trunk line between said exchanges, said trunk line terminating in relay switching equipment in said sub-exchange and in a non-numerical line switch in said main exchange, other automatic 45 switches in said main exchange, a home position for said line switch, circuit means for rendering said trunk line selectable for calls from said main to said sub-exchange when said line switch is in its home position, and circuit means for causing said line switch to step out of its home position in search of an idle one of said automatic switches when the trunk is seized through the switching equipment of the sub-ex- 50 change.
8. In a telephone system, a main and a sub-exchange, subscribers' lines terminating in each exchange, trunk lines between said exchanges, switching equipment in said exchanges, means for extending a talking connection between a main and a sub-exchange subscriber by way of one of said trunks and through certain of said switching equipment, and means at said main exchange for controlling the release of said sub and main 70 exchange equipment involved in the connection.
9. In an automatic telephone system, a main and a sub-exchange, a trunk between said exchanges, a branch of said trunk terminating in a toll board, automatic switching devices in said exchanges, subscribers' lines terminating in said exchanges, means for operating said switching devices to extend main to sub-exchange calls over said 80 trunk line, battery current for said sub-exchange switching devices being fed over said trunk line, and means enabling an operator at said toll board to seize said engaged trunk by way of its branch and to 85 release said established connection by interrupting the battery supply in said trunk.
10. In a telephone system, a main and a sub-exchange, switching devices in said exchanges, subscribers' lines terminating in said exchanges, a trunk line between said exchanges, means for establishing a talking connection between a main and a sub-exchange subscriber over said trunk line, circuit means such that the battery current for 90 operating said sub-exchange switching devices is supplied from the main exchange over said trunk, said circuit means being so arranged that the hanging up of the receiver of the sub-exchange telephone releases a relay in the main exchange by opening one side of said trunk and that the sub-exchange switching devices are released by 95 the subsequent opening of said trunk line by means controlled by the deenergization 100 of said relay.
11. In a telephone system, a main and a sub-exchange, subscribers' lines terminating in said exchanges, a trunk line between said exchanges, automatic switches in said main exchange, relay switching equipment in said sub-exchange, means responsive to a certain number of digits sent from a calling one of said main exchange subscribers' lines for 110 extending that line through certain of said automatic switches into connection with a called one of said main exchange subscribers' lines, and means responsive to the same number of digits sent from said calling line for extending that line through certain of 115 said automatic switches, over said trunk line through said relay switching equipment, and into connection with a called one of said sub-exchange subscriber's lines.
12. In a telephone system, a main and a 120
- 125
- 130

sub-exchange, subscribers' lines terminating in each exchange, trunk lines between said exchanges, switching equipment in said exchanges, means for extending a talking connection between a main and a sub-exchange subscriber by way of one of said trunks and through certain of said switching equipment, and means at the main exchange controlled by either the calling or called party for releasing all equipment involved in the connection. 10

In witness whereof, I hereunto subscribe my name this 12th day of June, A. D. 1925.

FRITZ LUBBERGER.
